United States Patent Office.

EZEKIEL D. SANFORD, OF BALTIMORE, MARYLAND

Letters Patent No. 66,045, dated June 25, 1867.

IMPROVED CLOTHES-DRYER.

The Schedule referred to in these Letters Patent and making part of the same.

TO ALL WHOM IT MAY CONCERN:

Be it known that I, EZEKIEL D. SANFORD, of the city and county of Baltimore, in the State of Maryland, have invented a new and useful Improved Adjustable Clothes-Frame; and I do hereby declare the following to be a full, clear, and exact description of the same, reference being had to the accompanying drawings, which are made part of this specification.

The object of my invention is to so construct a clothes-drying frame that the operator may stand at one point and fill the frame, and then elevate it so that persons may pass beneath it, and that it may be in a better position to receive the rays of the sun and the action of the wind; also, to so construct the apparatus that it may be folded up so as to occupy but a small space when not in use, and so that when hoisted it may be free to revolve by the action of the wind, so as to more rapidly dry the articles upon it.

Figure 1 is an elevation with part of the upper end of the standard broken away, so as to show the mode of supporting the hoisting-pulley.

Figure 2 is a horizontal section on line $z z$, fig. 1.

A represents the standard or post on which the rack slides, and which is supported in the socket B, on the bed-frame C, by the lateral braces D. The frame C is composed of two pieces of heavy board, mortised together at their centre, at which point they are fastened by buttons, pins, or other suitable means. These pieces are also provided with notches or shoulders at about midway between their centre and ends for the reception of the lower ends of the braces D, whose upper ends rest against and under the shoulder b on the socket B, which is rigidly attached to the bed-frame at its centre. The above arrangement may be dispensed with when the device is made a permanent fixture, as in that case the post may be simply set in the ground and be provided with a shoulder at the proper height to answer the purpose of the upper end of the socket B. E is a metallic bolt, which passes through the block f, and is secured in the top of the post A, and on the head of which the metallic plate f' rests and revolves. This plate is rigidly attached in the head, F, in which the pulley G is journalled, and whose lower end forms a sleeve, H, which fits over the end of the standard A to strengthen the head and prevent rocking. I is a sliding-box, on which the collars J J' are attached. The collars J have horizontal holes or depressions, in which the ends of the rods K are set; and they may have additional oblique ones, through which, alternately with the rods K, a rope or wire may be passed, so as to prevent the displacement of the rods longitudinally, and, at the same time, allow a free lateral and perpendicular movement; or, the rods K may be provided with brace-rods, attached to them by pins or pegs, so as to hold them taut at right angles. The lower one is also provided with a hook or pin, L, on which the loops M of the rope N are consecutively fastened in raising the rack, as will be hereafter more fully described. The rope N may be made shorter than shown, and provided with a button on its extreme lower end, by which it may be fastened to a loop on collar J' when the rack is resting on the socket B. The collar J' has perpendicular holes for the reception of the hoisting and suspending-ropes. The rods K are suspended at their outer ends by ropes O, the upper ends of the upper ones of which are attached to the collar J', and, at a proper distance below, to the upper tier of rods K; and, extending below them, are provided on their ends with buttons o, which are hitched into loops on the ropes attached to the second tier of rods, which are also provided with buttons o' on their lower ends, which hitch into loops on the lower tier. It is not, however, necessary to connect the rods in this precise manner; but I prefer it, as by this means the device is more readily taken apart and put together than when a single rope is used; and also by this means I need attach only as many tiers of rods as are necessary. The rods K are provided with a series of holes, L, or pins, through or around which the clothes-lines P pass. The ends of these lines are fastened together by sliding buckles p, which form a simple and effective means for tightening. These lines may, however, be supplanted by small wooden rods or wires, in which case they would be fastened to each of the rods K by pins or pegs; or, rods and lines may be used together on the same rack, as desired. Q is a weight or box, in which a quantity of weighty material may be placed, (the latter form being preferable) which may be attached to either one of the loops M to aid in hoisting the rack when it is filled with clothes.

The operation is as follows: The rods with their connecting-lines, being connected to the sliding-sleeve or box, are drawn down to the full extent of their supporting-ropes; and by forcing them out to their utmost

points, (at right angles,) as shown in fig. 2, and securing them, as described, the lines are rendered taut and ready for the reception of the articles to be attached to them. The weight-box is then attached; and, the rack being in position, as shown in fig. 1, the operator may begin to fill the lines on the upper tier of rods, turning the rack as it becomes necessary to reach different parts of it. After the first tier has been filled the hoisting-rope will be drawn down until the second loop may be hooked over the pin on the lower collar of the sliding-box, when the second tier will be in the same position as the first was, when it may be filled in the same manner as the first, and so on until all the lines are filled, when the rack may be hoisted to the top of the standard, and secured there in the same manner as in the other positions. The weighted box may be then removed, and the loose rope tied up on a belaying-pin, or thrown upon the rack. When in this position the rack and pulley revolve with the least breeze, thus securing the thorough sunning and drying of the articles on all parts of the rack. The weight of a rack ten feet square, having three tiers of rods, will be about seventy-five pounds; and it will hold about ten dozen of clothes, which, when wet, will weigh, on an average, fifteen pounds per dozen, making the weight of the rack, when filled with wet clothes, about two hundred and twenty-five pounds; and the amount of weight in the box should be regulated so as not to be more than one-half of that amount, as the operator could easily raise from seventy-five to one hundred and twenty-five pounds; and if the box is too heavily weighted it would be apt to raise the rack quicker than desirable. The weight may, however, if desired, be so regulated as to balance, or nearly so, the weight of the loaded rack. The rack when not in use may be folded up against the standard and secured there, or the whole device may be taken apart and stowed away, the sliding-box or sleeve being (when so desired) made in two parts and hinged, so as to be more easily removed. The same device, with a slight change in construction, may be used for drying wool, fruit, &c., or for "clothes-horses," racks, awnings, tent-frames, &c.; or, as a clothes-dryer, may be so constructed as to be used in the house.

Having thus described my invention, what I claim as new, and desire to secure by Letters Patent, is—

1. The revolving rack composed of the tubular sliding-box I, collars J J', rods K, supporting-ropes O, and clothes-lines P, or their equivalents, when constructed and operated substantially as and for the purpose described.

2. In combination with the sliding-rack of a clothes-dryer, I claim the weighted box Q, constructed and employed substantially as described for the purpose specified.

3. The arrangement of the rack I J J' K O P, post A, socket B, bed-frame C, and braces D, with the rope N, loops M, weight Q, and pin or hook L, combined and operating substantially as and for the purpose set forth.

To the above specification of my improvement I have signed my hand this fifteenth day of April, 1867.

E. D. SANFORD.
